INSTRUMENT PANEL FOR A STERILIZER

John A. Salvia, Rochester, N.Y., assignor to Wilmot Castle Company, Rochester, N.Y., a corporation of New York

Filed Oct. 21, 1964, Ser. No. 82,269

Term of patent 14 years

(Cl. D83—1)

FIG. 1 is a front perspective view embodying my new design for an instrument panel for a sterilizer; the broken lines are shown for illustrative purposes only; and

FIG. 2 is a front elevational view thereof.

I claim:

The ornamental design for an instrument panel for a sterilizer, substantially as shown and described.
